UNITED STATES PATENT OFFICE

FRED J. BLACKBURN, OF COLUMBUS, OHIO, ASSIGNOR TO THE FEDERAL GLASS COMPANY, OF COLUMBUS, OHIO, A CORPORATION OF OHIO

DESIGN FOR A TUMBLER OR ARTICLE OF SIMILAR NATURE

Application filed March 12, 1929. Serial No. 30,432. Term of patent 14 years.

To all whom it may concern:

Be it known that I, FRED J. BLACKBURN, a citizen of the United States, residing at Columbus, in the county of Franklin and State of Ohio, have invented a new, original, and ornamental Design for a Tumbler or Article of Similar Nature, of which the following is the specification, reference being had to the accompanying drawing, forming a part hereof;

I claim:

The ornamental design for a tumbler or article of similar nature, as shown and described.

FRED J. BLACKBURN.
